UNITED STATES PATENT OFFICE.

HARRISON J. L. FRANK, OF DETROIT, MICHIGAN, ASSIGNOR TO MUTUAL ELECTRIC AND MACHINE COMPANY, OF DETROIT, MICHIGAN, A CORPORATION OF WEST VIRGINIA.

ELECTRIC SWITCH.

Application filed September 17, 1921. Serial No. 501,368.

This invention relates to the construction of that type of switch boxes in which all the contacts are entirely enclosed but may be operated by means of a handle on the outside of the box, and its object is to provide a simple and reliable construction which may be locked against operation or against access as may be desired and in which a plurality of rigidly connected switches are operated simultaneously.

This invention consists in a box in which switch members are mounted on a base of insulating material, the switch members consisting of knife-blades, pivots therefor and contacts to receive the knife-blades, said knife-blades being rigidly connected by means of a metal bar covered with a shell of insulating material, and an operating member journaled in opposite sides of the box with the line of its journals parallel to the line of pivots of the switches, the operating member constituting a bail between its journals and the connecting bar having its ends formed to fit around the ends of the bail.

It further consists in forming one side of the box with a slot to permit the operating member to be inserted and in a stop plate formed with a bearing for the operating member and with stops to limit its movement.

It also consists in the details of construction illustrated in the accompanying drawings and particularly pointed out in the claims.

In the accompanying drawings, Fig. 1 is a front elevation of this improved box with the cover open. Fig. 2 is a side elevation thereof. Figs. 3 and 4 are sections on the lines 3-3 and 4-4 of Fig. 1 respectively. Fig. 5 is a section on the line 5-5 of Fig. 2. Fig. 6 is a section on the line 6-6 of Fig. 11. Fig. 7 is an elevation of the blank for the switch-blade connector bar. Fig. 8 is an elevation of a switch blade. Fig. 9 is a perspective view of a connector bar with a blade attached thereto. Fig. 10 is a perspective of a stop-plate. Fig. 11 is a side elevation of a slightly modified type of switch box. Fig. 12 is a section on the line 12-12 of Fig. 1. Fig. 13 is a front elevation of this switch provided with a modified type of connecting bar between the knife blades. Fig. 14 is a section on the line 14-14 of Fig. 13. Figs. 15 and 16 are elevations of

a knife edge-designed for this type of switch, Fig. 16 showing the connector bar in position. Fig. 17 is a perspective of this connector bar. Fig. 18 is a perspective of this type of connector bar with a metal plate connected to it to engage the operating member. Fig. 19 is an elevation and Fig. 20 a perspective view of another form of operating member. Fig. 21 is a detail of a bearing plate.

Similar reference characters refer to like parts throughout the several views.

The box in which the switch is mounted is preferably rectangular of any desired proportions and size, that shown having a back 1, sides 2 and 3, and ends 4 and 5. The ends are notched and closed by the usual end plates 6 having struck-up tongues 7 to secure these plates in position. The cover 8 is hinged to the side 2 and 9, and when closed down, prevents removal of these plates. A resilient latch 10 secured to the side 3 is adapted to extend through a slot in the cover and has a hole 11 to receive the hasp 12 of a padlock. It also preferably has a struck-up detent 13 which normally holds down the cover.

Secured to the back 1 by the screws 14 is a block 15 of non-conducting material such as slate or porcelain, to which are secured the terminals 16 and 17 for the knife-blades 18, the sockets 19 for the fuse plugs 20 and the terminals 21 for the service wires 22. The line wires 23 connect to the terminals 16. A connection 24 may be attached to the side 3 to ground the box. A connector 50 (Fig. 12) is attached to each central terminal 51 of the fuse socket 19 and to each support 16 of the knife-blades 18, a screw 52 securing this support in position. Wax 53 or other sealing material prevents access to this connector. The construction thus far described is well known.

In order to open and close the switches by swinging the knife-blades 18, I prefer to form a connector bar by stamping out a blank 25 having arms 26 at its ends, and wind the same with a sheet of fusible insulating material 27, such as paper impregnated with shellac. This connector bar and its winding are then baked to fuse the gum and the bar is then slipped into the notch 28 in the knife blade between the fingers 29 thereon which are then pinched onto the bar. The fused insulation is very hard and

permanently united to the bar so that there is little danger of injury thereto when the fingers are brought together as shown in Fig. 9.

5 The operating device for the switch comprises a crank 30, two journal portions 31 and 32 and a handle 33. The side 2 is formed with a hole to receive the journal 31, but the side 3 is formed with a slot 34 through which the crank 30 may be introduced. A stop-plate 35 is formed with a drawn bearing 36 for the journal 32 and is slipped into place before the bail is inserted through the slot 34. The plate 35 is preferably formed with a dowel 36^a to extend into this slot, as indicated in Fig. 5, to position the plate which is spot-welded into place after the parts are assembled. When the operating crank and the pivots of the 20 knife-blades are out of alinement, the arms 26 on the connector bar 25 have sliding engagement with the crank arms 41.

The stop-plate has stops 37 and 38 to limit the movements of the handle and the 25 switch members. The stop 37 is preferably formed with a slot 39, sufficiently long to receive a series of padlock hasps which will extend around the operating handle and prevent the switch being closed without the 30 knowledge of all those concerned, such as the lineman, foreman and inspector. These stops 37 and 38 are positive and cannot get out of order, an important factor in devices of this character.

35 I prefer to assemble the box and operating handle and bail including the stop plate and enamel the assembled structure. The end plates and connector bar are enameled separately and the latter then attached to 40 the knife-blades, after which the switch is assembled and inserted and secured within the box, the arms 26 being curved if desired as indicated in Figs. 3 and 4. These arms 26 are notched or forked to engage the crank 45 arms 41 of the operating crank.

Instead of a longitudinal slot 34, the side 3 may be formed with a slot 42 at right angles to its edge to permit free introduction of the journal portion 32 of the operating device. In this case the stop-plate 43 may be formed with an extension 44 to cover this slot and with a dowel 45 to fit the slot to position the plate. This plate may also be formed with small dowels 46 to fit holes 55 47 in the side 3 to position the plate before it is spot welded into position. An additional pair of dowels are indicated by the small circles 48 in Fig. 11 at each side of the slot indicated by the dotted lines 49, 60 which dowels fit into holes in the metal of the side of the box and thus bridge this slot. The switch mechanism and the operating device may be the same as above described.

In Fig. 1 I have shown springs 50 extending from the connector bar 25 to the

operating crank which normally holds the shoulders 51 at the lower ends of the notches 52 against the side arms 41 of the crank. When however the switch is to be opened, the friction of the knife blade in the contacts 16 is such as to permit the side arms to move up to the shoulders 53 against the tension of these springs. Continued movement of the crank moves the knife blades out of engagement with these contacts, and at the instant such engagement is broken the springs act to accelerate the movement of these knife blades and break the arc at the points of disengagement.

Instead of a metal bar covered with insulation a solid connector bar 55 of insulating material may be employed. This bar is preferably formed with grooves 56 to receive the ears 57 on the knife blades 58 and the ends of these ears when bent down as shown in Fig. 16, secure the bar to the knife blades.

In Figs. 13 and 14 a connection is shown which is available to cause the crank 59 to swing this bar 55. It consists of a plate bent 90 to constitute a cylinder 60 to receive the side arm 61 of the crank and two ears 62 between which the end of the connector bar extends.

In Fig. 18 a forked plate 64 is shown engaging the side arm 65 of the operating crank, this plate having clamping fingers 66 and 67, the former being bent into one of the grooves 56 of the bar 55.

Instead of forming the operating crank of a single piece of round metal it may be sheared from a flat plate and bent to constitute the crank 70 having side arms 71 from which the ears 72 extend on each side of the ends of the bar 55. The ends of the plate are bent to form journals 73, one of which may be made long enough to receive the operating handle 74. The same stop plate 35 with its stop lugs may be used to provide a bearing for the journal which extends into the handle 74.

Instead of having the bearing for the adjacent journal of the operating crank extending outwardly, from the bearing plate 35, as does the part 36 in Fig. 6, this bearing may extend inwardly, as does the part 76 in Fig. 21, in which case the slot in the side of the box is made large enough to receive this bearing.

The proportions and details of the several parts of this device may all be changed by those skilled in the art without departing from the spirit of my invention as set forth in the following claims.

I claim:

1. In combination, stationary switch contacts, movable knife-blade members adapted to engage therewith and formed with pairs of fingers along one edge, alined pivots for said knife-blade members, a metallic connector bar having forked ends and a shell of

- insulation adapted to be received between said fingers which are closed onto said bar and insulation, and an operating crank for said knife-blade members comprising side arms adapted to be slidably received in the forked ends of the connector bar.
2. In combination, stationary switch contacts, movable knife-blade members adapted to engage therewith, alined pivots for the 10 knife-blade members, a flat connecting bar and a shell of insulating material thereon, said knife blade members having pairs of fingers between which said bar is received and which are closed around the bar and the 15 insulation thereon, an operating crank consisting of a pair of arms, a cross bar, and a handle to swing the crank, said connecting bar being formed with forked ends to engage said crank arms to be swung thereby.
- 20 3. In combination, stationary switch contacts, movable knife-blade members adapted to engage therewith, alined pivots for the knife-blades, a metallic connector bar and a shell of insulation thereon attached to the 25 knife-blades a distance from their pivots, and a crank having two crank arms whose axis is parallel to that of the knife-blades, said connector bar having forked ends slidably engaging the crank arms to be actuated 30 thereby to swing the knife-blades.
4. In combination, stationary switch contacts, movable knife-blade members adapted to engage therewith, alined pivots for the knife-blades, a connector bar attached to the 35 knife-blades a distance from one end and insulated therefrom, and a crank having two crank arms engaged directly by the ends of the connector bar whereby the knife-blades
- may be swung to open and close the switch.
5. In combination, stationary switch contacts, movable knife-blade members adapted to engage therewith, alined pivots for the knife-blades, a connector bar and a shell of insulating material composed of a convolutely wound strip of fibrous material and 40 plastic insulation secured to said bar, said knife-blades having slots in their upper edges a distance from their pivots to receive the connector bar and the insulation thereon and also having fingers adapted to be bent 45 together over said connector bar to hold it in position, and means engaging the ends of the connector bar to swing the knife-blades.
6. In combination, an electric switch and the casing therefor having opposite side 50 walls, a switch operating member comprising a crank within the casing and a handle without the casing, and a stop plate on the operating member between the handle and crank providing a bearing for said operating member and having two integral rigid stops extending from its edges into the path of the handle to limit the movements of the handle, one of said stops being apertured to receive a lock whereby the handle may be 55 secured to said stop.
7. In a switch, a pair of movable knife-blade members having pairs of fingers projecting from one edge and a connector bar adapted to be secured to said knife-blades 60 by bending together the fingers to grip the bar, said bar having a metal inner portion with a strip of paper wound convolutely thereon and impregnated with and secured to said bar by means of shellac.

HARRISON J. L. FRANK.
